UNITED STATES PATENT OFFICE

2,482,219

RAILWAY TRUCK BOLSTER COLUMN GUIDE

Harvey H. Shaffer, Berwick, Pa.

Application September 26, 1945, Serial No. 618,722

1 Claim. (Cl. 105—207)

1

This invention relates to column guides for use in connection with the truck bolsters of railway rolling stock.

Heretofore, the column guides and the posts engaged thereby have been integral portions of the parts from which they are extended and, as a result of the relative up and down movement of the posts and the guides, wear has been created which it has been difficult or impossible to overcome.

An object of the present invention is to provide a new and novel arrangement of cooperating posts and guides so constructed that, in the event of excessive wear, the guides can be removed from their supporting structure and new guides substituted therefor, these guides being automatically locked in position.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

In the accompanying drawings, the preferred form of the invention has been shown.

In said drawings,

Figure 1 is an elevation of a portion of a side frame and a section through a portion of a truck bolster, these parts being equipped with cooperating elements such as constitute the present invention.

Figure 2 is a section on line 2—2, Figure 1.

Figure 3 is an enlarged section on line 3—3, Figure 2.

Figure 4 is an elevation of a portion of the truck bolster, the guide therein being broken away.

Figure 5 is a section on line 5—5, Figure 3.

Referring to the figures by characters of reference, 1 designates a portion of the side frame forming a part of the railway car and this side frame has column posts, one of which has been indicated at 2. The column post has a concave shallow channel 3 forming a bearing surface at opposite sides of which are converging flat bearing surfaces 4. All of these bearing surfaces are extended along substantially vertical lines.

A portion of a truck bolster has been indicated at 5 and each end thereof is formed with a dovetailed channel 6 closed at the top by an abutment or shoulder 7 against which is adapted to be seated a block 8 constituting a guide and which

2

is proportioned to fit snugly within the channel 6. This block or guide 8 has an intermediate convex bearing surface 9 proportioned to fit snugly against the concave bearing surface 3 of the column post and said bearing surface 9 constitutes the inner wall of a recess in the guide or block 8. The side walls 10 of this recess diverge outwardly and are adapted, when the guide and the column post are assembled, to be positioned parallel with and in sliding contact with the surfaces 4 of the post.

The inner or back wall of the channel 6 is flat and the block or guide 8 is adapted to fit snugly thereagainst when in position in the channel. 15 Reinforcing and guiding ribs 11 can be formed on the inner wall of the channel 6 and these are adapted to be seated in corresponding grooves 12 in the guide 8.

Formed within the truck bolster 5 and the 20 guide 8 are matching upwardly extending grooves 13 and 14 respectively. The groove 14, which is formed in the guide 8, has recesses 15 and 16 at its respective ends. In one of these recesses, namely the recess at the upper end of the groove 14, 25 there is anchored the offset end 17 of a leaf spring 18 which thus is suspended within the groove. The lower end of the leaf spring has a lip 19 which is adapted to enter the recess 16 when the leaf spring is flattened out within the groove 14. Normally, however, the leaf spring is sprung back into the groove 13 so that the lip 19 overlies and is supported close to the lower end wall of groove 13 as indicated at 20.

In practice the guide block is slid upwardly within the channel 6, at which time spring 18 is held under tension. As soon as the guide block 8 abuts the shoulder 7, the spring 18 will snap outwardly into the groove 13 and above the end wall or shoulder 20 so that the guide 8 thus will be locked in position in the truck bolster 5 as shown particularly in Figure 3. Consequently, as the frame and the truck bolster move upwardly and downwardly relative to each other, all wear therebetween will be taken up by the post 2 and the guide 8 and when excessive wear results, a suitable tool can be inserted into an opening 21 and pressed against spring 18 so as to disengage the spring from the end wall or shoulder 20, thereby permitting withdrawal of the guide block 50 from its seat in the groove 6.

What is claimed is:

In a railway car construction, the combination with a column post having bearing surfaces extended along substantially vertical lines, of a truck bolster having a channel, a guide block

3
 insertible upwardly into said channel and retained in part by the walls thereof, said channel being closed at its upper end to provide a terminal seat for the guide block, said guide block having bearing surfaces for snug and wiping contact with the bearing surfaces of the post, there being matching grooves within the guide block and the bolster, a spring, a portion of the spring being secured in one of the grooves, and a portion of the 10 spring being adapted for movement from said one of the grooves into the other groove, thereby to hold the guide block against withdrawal from the channel, there being an opening in the bolster for the reception of a tool to shift the latter spring portion from said other groove into said one of 15 the grooves, thereby permitting the withdrawal of the guide block.

HARVEY H. SHAFFER.
